US00D998152S

(12) **United States Design Patent** (10) Patent No.: **US D998,152 S**
(45) Date of Patent: ** Sep. 5, 2023

(54) **VEIN IMAGER CRADLE**(71) Applicant: **AccuVein Inc.**, Cold Spring Harbor, NY (US)(72) Inventors: **Ron Goldman**, Cold Spring Harbor, NY (US); **Fred Wood**, Medford, NY (US); **Vincent Luciano**, Shoreham, NY (US)(73) Assignee: **AccuVein, INC.**, Medford, NY (US)(**) Term: **15 Years**(21) Appl. No.: **29/756,544**(22) Filed: **Oct. 29, 2020****Related U.S. Application Data**

(63) Continuation of application No. 16/595,750, filed on Oct. 8, 2019, which is a continuation of application No. 15/678,355, filed on Aug. 16, 2017, now Pat. No. 10,518,046, which is a continuation of application No. 14/718,422, filed on May 21, 2015, now Pat. No. 9,789,267, which is a continuation of application No. 13/778,426, filed on Feb. 27, 2013, now Pat. No. 9,061,109, which is a continuation of application No. 12/804,506, filed on Jul. 22, 2010, now Pat. No. 8,463,364.
